Inventor:
George H. Abbott
By *Blawny & Blawny* Attn:

UNITED STATES PATENT OFFICE.

GEORGE H. ABBOTT, OF ELGIN, ILLINOIS, ASSIGNOR TO WOODRUFF & EDWARDS CO., OF ELGIN, ILLINOIS, A CORPORATION OF ILLINOIS.

FURNITURE.

Application filed January 7, 1924. Serial No. 684,707.

To all whom it may concern:

Be it known that I, GEORGE H. ABBOTT, a citizen of the United States, residing at Elgin, in the county of Kane and State of Illinois, have invented certain new and useful Improvements in Furniture, of which the following is a specification.

This invention which relates generally to furniture has particular reference to school desks and seats of the kind which use a standard in pedestal form, the purpose being to provide a serviceable, ornamental, and dependable device of this character on which may be mounted for plus and minus vertical adjustments a seat, as well as a desk, many of the parts being interchangeably constructed.

In many respects the construction herein described is similar to that set forth in a pending application of Alfred D. Edwards and myself, filed July 29, 1922, as Serial No. 578,483; the present invention, however, is possessed of certain improvements and special features of construction to 25 which detailed reference will hereinafter be made.

An exemplification of this invention is set forth in the accompanying drawings wherein:

30 Figure 1 is a side view, partly in elevation and partly in section, of the standard, together with seat and desk brackets mounted thereon;

Fig. 2 is a transverse section therethrough taken approximately on line 2—2 of Fig. 1;

Fig. 3 is an elevation of one end of the standard, the brackets being removed therefrom;

Fig. 4 is a perspective view of the nut 40 which forms one component of the adjustable connection between the standard and one of the brackets associated therewith;

Fig. 5 is a view in elevation of the bracket end which engages the standard;

Fig. 6 is a view in perspective looking toward the rear side of the rack bar which comprises one element in the bracket adjusting means; and

Fig. 7 is an enlarged fragmentary detail 50 in perspective of the standard end adjacent the lower extremity of one slot therein.

The major elements of this invention comprise a standard or support in the form of a pedestal A on which are mounted seat

and desk brackets B and C, respectively. 55 It is contemplated that suitable seat and desk fixtures (not shown) will be secured to the brackets when the furniture is ready for use. As shown, the cross sectional contour of the walls forming the standard is elliptical with its long axis extending from front to rear, and from the lower standard end, which is flared outwardly to provide a base 10, these walls taper inwardly toward the upper end which may be closed by a top or cross wall 11. A vertically extending slot 12 is formed in the front wall of the pedestal, as is also a similar slot (not shown) in its rear wall, these two slots extending for a substantial distance in the middle region of the standard. The general construction of the standard and its two brackets as described above forms no part of this invention but is made the subject of the pending application above referred to.

The seat bracket may be formed from an integral casting, or from companion castings, or otherwise, and is suitably configured on its top for the support of the seat fixture per se. The walls of this bracket are extended downwardly therefrom and rearwardly toward the tapering front side of the pedestal. The bracket sides 13, two in number, each extend toward the pedestal and provide between them an open space such that their rearward edges 14 are adapted to engage with the standard at relatively separated points. I prefer to form each of these rearward edges with a pair of bearing points 15 disposed, by preference, adjacent opposite ends of these edges, thus providing a total of four bearing points upon the rearward edges 14 of the bracket. It is also preferred that the standard walls be provided with four elongated shoulders 16, one adjacent each rearward edge 14 of each bracket so as to receive contact from two of the bearing points 15. In this manner each bracket is assured of engagement with the standard at four definite points, such as to be guided and held properly in any of the positions wherein it may be adjustably secured. Additional to the points of contact already mentioned, 95 I may provide inner bearing points 17 (see Fig. 5), four in number for each bracket, one of these inner points of contact being

shown as adjacent each rearward bearing point 15. With such a construction, the bracket may engage the standard at four points intermediately of the shoulders 16 to thereby maintain a firm contact with the standard. Since it is customary to produce both the standard and brackets from unfinished cast metal, the resulting uneven surfaces will tend to prevent a smooth seating of the brackets upon the standard, but by providing a few raised points of contact arranged in a definite relation, a more satisfactory mounting of the brackets upon the standard may be effected.

15 The preceding description which has been confined almost wholly to the seat bracket B applies equally to the desk bracket C, which in all substantial respects is identical therewith.

20 For securing each bracket upon the pedestal in any desired position of adjustment, I provide means as follows: A bolt 20 is inserted through a suitable lateral opening 21 formed in the front bracket wall which 25 may, if desired, be thickened at that point for additional strength. The bolt head 22 is shown as rested against a washer 23 which may be positioned within a suitable seat therefor. It is preferred that the opening 21 should be slightly elongated in a 30 vertical direction, as indicated in Fig. 5, for purposes which will be presently explained. The bolt shank is screw-threaded to engage with a nut 24 from which are 35 extended in spaced relation two arms 25 connecting with an enlarged head 26. A nut of this description is adapted for association with the slot 12 of the standard, its two arms being receivable therewith 40 so as to present the head 26 against the inner face of its walls. The nut in its entirety is accordingly secured both against rotation and end thrusts when the bolt is tightened against the bracket.

45 I provide means for raising and lowering the bracket upon the standard which may embody the following construction. Through the front bracket wall, preferably above the opening 21 therein, is a second 50 opening 30 tapering outwardly from front to rear. Inserted into this opening, from the rear end thereof, is a rotatable member 31 having at its outer end a polygonal formation 32 for convenient engagement by a wrench. At its enlarged inner end is a 55 head 33 provided with a spiral rib 34 constituting a worm. The axis of rotation of the member 31 is obliquely disposed in relation to an adjacent rack bar 35 whereon 60 are formed teeth adapted to be engaged by the spiral rib at one point in its periphery. This rack bar which extends lengthwise of the slot 12 and through the space between the nut arms 25 may be secured in place 65 within suitable seats 36 formed in the

standard wall adjacent each slot end, the bar extremities being provided with centering elements 37 adapted to rest in such seats and also, if desired, with faces 38 which bear upon the standard walls (see Fig. 6). 70

Referring now to Figs. 1 and 4, the nut is shown as provided at its outer end with an upstanding lip 40 adapted to be slidingly received within a recess in the bracket wall and to engage with a lug 41 depending 75 downwardly therefrom. The lip and lug constitute, in effect, a hook by which the bracket is supported on the nut independently of the bolt 20. This is of advantage during the operation of assembling the parts 80 which enter into the construction heretofore described, prior to applying the bolt 20 to the nut. To provide for the assembly within the bracket opening 21 of a nut so formed, this opening is elongated vertically, 85 as already stated, to permit the nut to be moved laterally as required, prior to tightening of the bolt therewithin.

It should be manifest that in the present structure I provide for a dual support of 89 each bracket, namely, the clamping pressure exerted by the bolt 20 upon the nut 24, and the engagement of the spiral rib 34 within the teeth of the rack bar. To effect a change 95 in position of the bracket, the bolt is first loosened following which a wrench is applied to turn the member 31 so as to raise or lower the bracket. When the bracket has been brought to the desired position, the nut 20 is again tightened with the result that the 100 relationship of the parts becomes permanent.

The parts just described are duplicated 105 for the desk bracket and accordingly like reference numerals might be applied to the corresponding set of elements used in connection therewith. These adjusting parts are furthermore interchangeable such that either set may be used for the operation of the other bracket. In addition, either bracket may be changed around to occupy 110 the position of the other, since the pedestal formation is duplicated on both its front and rear sides.

In the raising and lowering movements of 115 the two brackets, it will be noted that each is independent of the other. A plus and minus adjustment is provided for, however, due to the sloping character of the front and rear walls of the pedestal, so that as the seat is raised, it is also moved rearwardly. In like manner the desk is moved forwardly as it is raised. With an opposite adjustment of the two brackets, a reversal 120 in these lateral movements is obtained. These changes in adjustment may be effected conveniently, with the aid of a socket wrench, and the parts to be manipulated are sufficiently accessible to not require any 125 change in position of the occupants. In ad-

dition the furniture article of this invention may be adjusted through a range sufficient to adapt the structure to persons of various sizes, and for accommodating persons of all ages only two sizes of the article will ordinarily be necessary.

A combined seat and desk of the kind described may be produced at a reasonable cost. In appearance it is attractive and the few places where dust, etc., may accumulate are easily reached for cleaning so that the article is advantageous from a sanitary standpoint as well.

I claim:

1. In a furniture article of the kind described, the combination of a standard having a vertically slotted wall, a bracket formed to rest against said wall, an apertured nut having a head adapted to engage the rear side of said wall, a bolt connecting the bracket with the nut, a rack mounted on the standard and extending through the nut aperture, and a worm device rotably mounted on the bracket adapted to engage with the rack in a manner to move the bracket vertically, substantially as described.

2. In a furniture article of the kind described, the combination of a standard having a vertically slotted wall, a bracket mounted to move vertically upon the standard wall, an apertured nut slidably secured to the standard, a bolt connecting the nut with the bracket a rack bar extending through the nut aperture and having a mounting on the standard, and a worm de-

vice co-operating with the rack adapted to raise and lower the bracket upon the standard, substantially as described.

3. In a furniture article of the kind described, the combination of a standard having a vertically slotted wall, a bracket mounted to move vertically upon the standard wall, an apertured nut slidably secured to the standard, a bolt connecting the nut with the bracket, and means for raising and lowering the bracket upon the standard comprising a rack mounted on the latter, extended through the nut aperture, and a rotatable worm carried on the bracket in operative relation to the rack, the worm having an operating portion exposed for manipulation, substantially as described.

4. In a furniture article of the kind described, the combination of a standard having a vertically slotted wall, a bracket adapted for adjustable mounting thereupon, a connection between the bracket and standard comprising a nut having arms extended in spaced relation rearwardly through the slot and a head bearing against the inner side of the standard wall, and a bolt engaging with the bracket and connected by screw threads to the nut, a rack bar positioned upon the standard walls parallel with the slot therein and intermediately of the arms of the nut, and a rotatable member removably carried by the bracket having a worm device in engagement with the rack bar for raising and lowering the bracket upon the standard, substantially as described.

GEORGE H. ABBOTT.
